UNITED STATES PATENT OFFICE.

KAMEZO TAIRA AND KIKUJIRO MASUDA, OF DENVER, COLORADO.

PASSENGER LIFE-BUOY.

1,276,826.

Specification of Letters Patent. Patented Aug. 27, 1918.

Application filed May 21, 1917. Serial No. 169,825.

To all whom it may concern:

Be it known that we, KAMEZO TAIRA and KIKUJIRO MASUDA, subjects of the Empire of Japan, residing at the city and county of Denver and State of Colorado, have invented 5 certain new and useful Improvements in Passenger Life-Buoys; and we do declare the following to be a full, clear, and exact 10 description of the invention, such as will enable others skilled in the art to which it appertains to make and use the same, reference being had to the accompanying drawings, and to the characters of reference 15 marked thereon, which form a part of this specification.

Our invention relates to improvements in life buoys, or what we prefer to term "passenger life buoys" for the reason that the structure is of such character that it may 20 have the necessary capacity for carrying a number of people. The ordinary size such as would commonly be carried by passenger vessels, would probably be of such size or capacity, to hold from a half dozen to a 25 dozen people with comfort.

Furthermore, the structure is of such character that when in use it may be quickly and easily collapsed whereby it may be confined within small compass and, therefore, 30 occupying but little room whereby it becomes practicable to store a considerable number of the devices upon the ordinary passenger steamer. The structure is composed of an outer covering of water-proof 35 material as canvas or other suitable relatively tough fabric which is held expanded when in use, by means of inner rings which for purposes of lightness may be composed of wood as bamboo, ratan or other suitable 40 tough material which may be bent into circular form. Any desired number of these rings or hoops may be employed. The body of the structure is substantially spherical in shape, the bottom, however having a flat circular 45 surface from which is built up a casing in which is journaled a spool with which a weight is connected by means of a rope or cable, the weight being employed as ballast or as a means for normally maintaining the 50 structure in the upright position. Extending upwardly from the base of the bottom structure are posts or stanchions which are

hinged at their lower extremities and also intermediate their extremities for collapsing purposes. The upper extremities of these 55 posts are suitably connected with the top of the collapsible structure and as illustrated in the drawing, form a support for auxiliary posts which extend upwardly through an opening in the top of the structure the auxiliary posts being also covered by the canvas or water-proof fabric and provided with windows or transparent members through which a lookout may be maintained if desired, the upper extremities of the auxiliary posts being 60 connected with a suitable water-tight closure, which, however, has a circular opening 65 through which projects an air-tube which may extend a suitable distance above the top in order to supply the occupants with 70 the necessary air.

Having briefly outlined our improvement, we will proceed to describe the same in detail, reference being made to the accompanying drawing in which is illustrated an embodiment thereof. In this drawing:

Figure 1 is a side elevation showing our improved life buoy in use.

Fig. 2 is a central vertical section of the structure, the parts being shown on a much 80 larger scale than in Fig. 1.

Fig. 3 is a horizontal section taken on the line 3—3 Fig. 2.

Fig. 4 is a section taken through the structure shown in the collapsed position and 85 within a container, the parts being shown slightly separated as distinguished from the completely collapsed position for the purpose of greater clearness of illustration.

The same reference characters indicate 90 the same parts in all the views.

Let the numeral 5 designate a horizontally disposed bottom plate which is circular in shape and provided with an opening 6. To the inner edge of the plate 5 are secured 95 upwardly projecting parts 7 in which is journaled a shaft or spindle 8 upon which is wound a cable 9, one extremity of which is attached to the shaft, while to its opposite extremity is attached a sectional weight 10 100 for purposes of ballast. This weight may be lowered to a considerable depth if desired or it may be kept nearer the surface, depending upon the conditions and require-

ments. To the upper extremities of the parts 7 is secured a cover 2, the entire bottom structure being of such character as to prevent the water from entering the enclosure. The shaft 8 is provided with a hand-crank 12 which is arranged within the structure and is accessible to the occupants and through the medium of which the ballast weight may be raised and lowered at pleasure.

Secured to the bottom plate 5 is the lower edge 13 of the water-proof canvas 14 which constitutes the cover of the structure. This edge 13 of the canvas is clamped between the plate 5 and a lower plate 15, through the medium of bolts 16 which are adjustable whereby a tight joint may be formed at the bottom of the apparatus. Above the bottom plate 5, we secure the canvas in any suitable manner to a series of interior hoops or rings 96 which vary in size according to their location, the one in the middle when the structure is expanded being the largest, the others above and below gradually getting smaller by virtue of the spherical form of the device. The upper edge of the body of the canvas is connected with a top ring 17 which may be made of a number of strands of rope or heavy cord, or of any other suitable material. We prefer, however, that the entire structure should be made of such material as to give the structure a relative high degree of buoyancy, and for this reason we prefer to avoid as far as possible the use of heavy material as metal, though it must be understood that we do not limit ourselves to any special material, or other details of structure illustrated in the drawing.

As illustrated, the top ring 17 surrounds a central opening 18 at the top of the structure and through this opening extend a number of auxiliary posts 19 which are fitted to the upper extremities of the main posts or stanchions 20 whose lower extremities are hingedly connected as shown at 21 with brackets 22 which are secured to the bottom plate 5. These main posts or uprights are normally secured in the upright position by means of spring actuated locking pawls or dogs which may be of any suitable structure. As shown in the drawing, pins 23 are slidably mounted in guides 24 and are each surrounded by a spiral spring 25, one extremity of which engages the upper guide, while its opposite extremity engages a stop 26 formed on the pin. By virtue of this structure, the spring acts upon the pin to force its extremity below the lower-most guide, into a recess 26 formed in the adjacent bracket, thus preventing the main uprights or stanchions 20 from moving out of their normal position, while the locking devices are in place (see Fig. 2). These uprights 20 are provided in-

termediate the extremities with joints formed by hinge pins 27 which are so connected with the adjacent extremities of the connected parts which for purposes of convenience we will respectively designate by the numerals 28 and 29, that these joints may be broken outwardly after the locking devices are released, thus permitting the collapsing of the structure (see Fig. 4) as will be hereinafter more fully described. The pins 27 pass through perforated lugs formed on metal parts 30 with which the adjacent extremities of the two parts 28 and 29 of each post are provided. The parts of the extremities of these posts which extend outwardly in a horizontal direction beyond the hinge pins, contain flat engaging surfaces whereby the posts are locked against breaking or moving inwardly by virtue of their jointed connection. Furthermore, when the structure is expanded and in use, the posts are further held in such position by means of connecting rods 31, two of the posts of each pair being connected by one of these rods, the posts having staples 32 which the hooked extremities of the rods engage in such a manner that the rods may be completely detached if desired when it becomes necessary to collapse the structure.

As shown in Fig. 3, particularly, of the drawing, the middle outer ring 26 which is directly in engagement with the inner surface of the canvas 14 is connected by means of expanding members 82 with a similar inner ring 33, the members 82 constituting spacers between the inner and outer rings, the inner ring being connected with each post or stanchion 20 by means of a number of cords or ropes 34 whose outer extremities are secured to the ring 33 at a number of points, while their inner extremities are connected with a ring 35, the latter in turn being connected by a flexible member 36 with the adjacent post 20 through the medium of a U-bolt 37 which is adjustable by means of a nut 38 for the purpose of tightening the structure and maintaining the inner ring in its proper relative position.

As shown in the drawing, the top auxiliary posts 19 are connected at their lower extremities with the upper extremity of the post 20, by means of brackets 39 which are secured to the posts 19 and project beyond the same on opposite sides forming a sort of groove to receive the upper extremities of the posts 20, these brackets having hooks 40 which interlock with pins 41 with which the upper extremities of the posts 20 are provided. The upper extremities of the auxiliary posts 19 are equipped with plates 42 which project inwardly and are perforated to receive locking bolts 43 whose upper extremities are connected as shown at 44 with a cover 45. To the body 14 of the canvas covering at the top is secured a can-

was extension 46 which completely surrounds the auxiliary posts 19, the lower portion of this extension 46 being held in place by an outer ring 47. The upper edge of the canvas extension 42 is bent inwardly as shown at 48 over the tops of the auxiliary posts 19, and this inner edge is clamped tightly between the top plates 42 of the auxiliary posts and the cover 45 through the medium of the locking bolts 43 whose nuts 49 are equipped with lever arms 50 to facilitate adjustment. Between the outer edge of the cover and the structure directly underneath, is located a packing ring 51 whereby a water-tight joint is formed. In the center of the cover 45 is formed an opening 52 from which extends upwardly an air pipe 53 whose lower extremity is threaded into a collar which is exteriorly flanged as shown at 54, and secured to the cover 45 by bolts 55. By virtue of this construction the top of the device will be completely closed except where the air pipe is located.

Secured to the lower member 29 of the posts 20, is an air pump 56 which is connected by means of a flexible conduit 57 with the atmosphere, said conduit passing through an opening 58 formed in the canvas 14, above the water level. This pump may be employed for the purpose of maintaining a circulation of air through the interior of the structure, when for any reason it may be necessary or desirable to do so.

When it is desired to collapse the structure the locking pins 23 are disengaged from the brackets 22, and the rods 31 which connect the posts are detached. Furthermore, the air pipe 53 is removed after which the lower extremities of the auxiliary posts are detached from the upper ends of the main posts, and when this is done the posts 20 may be broken outwardly on their hinges and the structure collapses within a suitable receptacle 59. It will also be understood that the ballast weight 10 may be removed when it is desired to collapse the structure into the smallest possible space.

When the form of construction illustrated in Fig. 2 is employed, that is, that including the auxiliary posts 19, a lookout may be maintained through windows 60 with which the canvas extension 46 is provided. In fact, this is the object of this extension feature. When it is not employed, the upper extremities of the posts 20 may be suitably connected with the upper ring 17 at the top of the structure, and the cover suitably connected or secured to the said top ring in such a manner as to form a watertight joint. In this case the air tube or pipe 53 connected with the cover, will be employed in the same manner as heretofore described. As shown in the drawing the cover is composed of a flat plate, a lower ring and an interposed gasket 51. The ring is pro-

vided with a lug 84 which is hingedly connected as shown at 86 with a lug or arm 85 which is secured to or formed integrally with the cover plate. By virtue of this construction the ring and plate parts of the cover may be separated when the cover is detached by removing the nuts 49 from the bolts 43.

As illustrated in the drawing (see Fig. 3), boxes 61 are secured to the bottom plate 5 on opposite sides of the windlass structure. These boxes have hinged lids and may be utilized for storing provisions.

When it is desired to expand the structure, a rope 62 connected as shown at 63 with one of the lower members 29 of one of the main posts may be utilized in connection with pulleys 64 mounted on the adjacent post members 29. By connecting this rope in the first instance with one of the pulleys of the member 29 opposite that with which the extremity of the rope is connected, a leverage may be maintained to facilitate the lifting of the structure for expansion purposes. Again, by connecting the rope 90 with a number of pulleys which are mounted on each of the two members 29, further power may be maintained on the principle of the ordinary block and tackle.

The structure for the purpose of launching from a ship, may be equipped with a flexible loop 65, which in turn may be connected with a float 66 by a rope 67, the float in turn being connected by means of a rope or cable 68 with an anchor 69. The structure may first be dropped from the ship when the parts 65 and 67 are in the position shown by dotted lines in Fig. 1 and after it has entered the water, the float and anchor may be dropped. The float should be of sufficient buoyancy to support the anchor in deep water, or in water of such depth that the anchor cannot reach the bottom with the float on top.

The structure is preferably further provided with a rope ladder 70 which is connected with the upper part of the structure at one extremity as shown at 71, while its other extremity is free to enter the water. This ladder will enable a person to enter the structure after it has been launched, through the aid of those on the inside who, of course, will have to loosen the cover by the manipulation of the fastening nuts 49. Or the ladder may be utilized to enable one or more persons to maintain themselves above the water and on the outside of the structure.

Attention is called to the fact that in Fig. 4 the top of the receptacle 59 is broken away to facilitate a better illustration of the structure which is not completely collapsed for the reason heretofore stated.

The rings or hoops 96 may be of any suitable structure. As shown in the drawing they are composed of a number of relatively

small hoop members which are wound exteriorly to form a sort of cable. It is important that they be composed of some relatively light material in order to add buoyancy to the structure, it being desirable to avoid the use of metal as far as possible. These rings or hoops 96 may be connected with the exterior canvas or flexible member in any suitable manner as by sewing through the canvas and extending the threads or other materials around the rings or hoops as shown at 83 (see Fig. 2). The canvas structure after the device is completed may be covered with water proof paint or varnish or any other suitable or desired substance in order to make it absolutely water proof. Hence, if in connecting the hoops to the canvas any small perforations are made they will be filled by the exterior coating of paint or other water proof substance.

Having thus described our invention, what we claim is:

1. A life buoy approximately spherical in shape comprising an inner jointed stanchion structure, expanding rings, and a flexible cover upon which said rings act, said rings being of varying diameter to maintain the spherical contour, the intermediate portions of the stanchion structure being spaced from the rings and the covering.

2. A life buoy approximately spherical in shape comprising an inner jointed stanchion structure, expanding rings, means for connecting the rings with said structure, a flexible cover, and means for connecting the rings with the cover, said rings being of varying diameter to maintain the spherical contour, the intermediate portions of the stanchion structure being spaced from the rings and the covering.

3. A life buoy approximately spherical in shape having an inner jointed stanchion structure, expanding rings connected with said structure, and a flexible covering also connected with said rings, said rings being of varying diameter to maintain the spherical contour, the intermediate portions of the stanchion structure being spaced from the rings and the covering.

50 4. Apparatus of the class described approximately spherical in shape including a rigid base, posts extending upwardly from said base, a flexible covering connected with the base and with the posts above the base, inner expanding rings connected with the covering, and means for connecting one of said rings with the posts, said rings being of varying diameter to maintain the spherical contour, the intermediate portions of the posts being spaced from the rings and the covering.

55 5. Apparatus of the class described including a rigid base, a flexible covering connected with the base, posts hingedly connected with the base and extending upwardly

therefrom, the posts being jointed and the covering being connected with the upper extremities of the posts, expanding rings of varying diameter engaging the covering above the base to form a structure approximately spherical in shape, and means for connecting one of the rings with the posts.

6. Apparatus of the class described including a base having a central opening, a boxed closure extending above the opening, a shaft journaled in said opening, a ballast weight, flexible means connecting said weight with the shaft, a flexible covering connected with the periphery of said base, posts secured to and extending upwardly from the base, the flexible covering being connected with the tops of the posts, expanding rings of varying diameter engaging the covering between the base and the top of the posts to form a structure approximately spherical in shape, a ring spaced inwardly from the median expanding ring, and flexible means connecting said inwardly spaced ring with the posts.

7. Apparatus of the class described including a base, a flexible covering connected with said base, posts extending upwardly from the base, the flexible covering being connected with the tops of the posts, expanding rings of varying diameter engaging the covering between the base and the tops of the posts to form a structure approximately spherical in shape, and a connection between the median ring and the posts.

8. Apparatus of the class described including a base, a flexible covering connected with the base, posts secured to and extending upwardly from the base, the flexible covering being suitably connected with the tops of the posts, auxiliary posts detachably connected with the main posts and extending above the same, an extension flexible covering for the auxiliary posts, windows in said extension covering, a top closure connected with the auxiliary posts, expanding rings of varying diameter engaging the covering between the base and the tops of the posts to form a structure approximately spherical in shape, and a connection between the median ring and the posts.

9. Apparatus of the class described including a rigid base, posts hingedly connected with the base and extending upwardly therefrom, adjustable means for locking the posts to the base, the posts being jointed to form a collapsible structure, a flexible covering connected with the base and the tops of the posts, expanding rings for the covering intermediate the post extremities, and means for connecting the median ring with the posts.

10. Apparatus of the class described including a rigid base, posts arranged in pairs their lower extremities being connected with

the base, rods connecting the posts of each pair above the base, a flexible covering connected with the base and the tops of the posts, expanding rings for the covering, said 5 rings being located intermediate the post extremities, and means for connecting the median ring with the posts.

In testimony whereof we affix our signatures in presence of a witness.

KAMEZO TAIRA.
KIKUJIRO MASUDA.
